Patented June 5, 1923.

UNITED STATES PATENT OFFICE.

HAROLD BRIX, OF CHICAGO, ILLINOIS, ASSIGNOR TO SHARP & SMITH, OF CHICAGO,
ILLINOIS, A CORPORATION OF ILLINOIS.

DETACHABLE-BLADE KNIFE.

Application filed January 20, 1922. Serial No. 530,598.

To all whom it may concern:

Be it known that I, HAROLD BRIX, a citizen of the United States, residing at 65 East Lake Street, Chicago, in the county 5 of Cook and State of Illinois, have invented a new and useful Improvement in Detachable-Blade Knives, of which the following is a specification.

This invention relates to improvements 10 in detachable blade knives, and more particularly to a device of that character in which the blade is made of thin sheet-metal, which is more or less flexible; so that the handle, in which the blade is mounted for 15 use, not only holds the blade, but also reinforces and stiffens it to a certain extent.

The invention will be fully understood by 20 reference to the following specification and accompanying drawing, in which Figure 1 is a view in side elevation of a device embodying the features of my invention, Figure 2 is a top plan view, Figure 3 is a view on an enlarged scale with one of the blades 25 removed from the handle, Figure 4 is a vertical sectional view of the handle, Figure 5 is a view similar to Fig. 4 showing the blade in place, and Figure 6 is a view taken as indicated by the line 6 of Fig. 4.

As shown in the drawings, the handle 30 of the knife comprises a hand-grip portion 10, having at one end a blade-supporting portion comprising two parallel prongs 11, separated by a slot 12. The two prongs 11 are joined near their ends by a pin 13, which extends across the slot 12.

Mounted in the part 10 of the handle 40 at the end where the prongs 11 join, is a circular spring 17 as shown. This spring 17 is put in place in a hole provided, and a plug 18 is then inserted to hold the spring in place.

In Fig. 3 is shown one of the blades 50. This blade is made preferably of thin 45 sheet-metal. Blades from such metal can be easily and cheaply made; and can ordinarily be stamped out in the shape shown. Such metal is usually more or less flexible. 20 indicates the cutting edge of the blade. 50 The upper edge 21 of the blade is provided with a downwardly and rearwardly extending notch or cut 22, adapted to accommodate the pin 13, when the blade is in place. The back end of the blade is convexly

curved, as indicated by 23. In this curve 55 and at about the center, is provided a recess or notch 24. The bottom of the rear edge of the blade is also provided with a depending tongue 26. The forward end of the part 10 of the handle, where it meets the rear end of the slot 12, is concavely curved, as indicated by 30, to correspond with the convex curve 23 on the rear end of the blade. The spring 17 is so located that it projects slightly into the slot 12, as 60 shown.

In operation, the blade 50 is placed in the slot 12 behind the pin 13, and moved so that the cut or slot 22 embraces the pin 13; so that it will be in position, as indicated 70 by the broken lines in Fig. 5. The back end of the blade is then pressed downwardly, causing the blade to rotate on the pin 13, until the notch 24 at the rear of the blade snaps over the spring 17. When in this position the convexly curved rear end 75 23 of the blade will be in contact with the concavely curved part 30 of the handle, thus preventing further downward movement of the back end of the blade; and the pin 13 will be at the inner end of the cut or notch 22. The blade will thus be firmly held in position for use. In removing the blade, upward pressure on the tongue 26 will release the notch 24 from the spring 17, 80 85 permitting the back end of the blade to be swung upwardly, so that the notch or cut 22 can be removed from the pin 13 and the blade lifted out.

It will be noted that the prongs 11 of 90 the handle are considerably thicker than the blade and extend forwardly more than half of the length of the blade. These prongs not only assist in supporting the blade in the handle, but also strengthen 95 and stiffen it and prevent bending of the blade in use.

While I have shown and described certain embodiments of my invention, it is to be understood that it is capable of many 100 modifications. Changes therefore in the construction and arrangement may be made without departing from the spirit and scope of the invention as disclosed in the appended claims, in which it is my intention 105 to claim all novelty inherent in my invention as broadly as possible in view of the prior art.

What I claim as new and desire to secure by Letters Patent, is:

1. In a device of the character described, a handle comprising a hand-grip portion and a blade-supporting portion, the blade-supporting portion comprising two parallelly arranged stiff prongs with a slot between adapted to accommodate a thin flexible blade, a pin joining the prongs near their ends, a thin flexible blade adapted to fit in the slot between the prongs, a notch in the upper edge of the blade adapted to embrace the pin joining the ends of the prongs, and a notch at the back end of the blade adapted to engage with spring means in the handle.
2. A thin flexible blade provided with a downwardly and rearwardly extending slot with parallel sides at its upper edge and having its back end convexly curved and provided with a notch.
3. In a device of the character described, a handle comprising a hand-grip portion and a blade-supporting portion, the blade-supporting portion comprising two parallelly arranged stiff prongs with a slot between adapted to accommodate a thin flexible blade, a pin joining the prongs near their ends, a thin flexible blade adapted to fit in the slot between the prongs and provided at its upper edge with a downwardly and rearwardly extending notch adapted to embrace said pin, and means for yieldingly pressing the blade forward to retain the pin in the notch.
4. In a device of the character described, a handle comprising a hand-grip portion and a blade-supporting portion, the blade-supporting portion comprising two parallelly arranged stiff prongs with a slot between adapted to accommodate a thin flexible blade, a pin joining the prongs near their ends, a thin flexible blade adapted to fit in the slot between the prongs and provided at its upper edge with a downwardly and rearwardly extending notch adapted to embrace said pin, and a notch at the back end of the blade adapted to engage with spring means in the handle.
5. In a device of the character described; a handle comprising a hand-grip portion and a blade-supporting portion; the blade-supporting portion comprising two parallelly arranged stiff prongs with a slot between adapted to accommodate a thin flexible blade; a pin joining the prongs near their ends; a thin flexible blade adapted to fit in the slot between the prongs and provided at its upper edge with a notch adapted to embrace said pin; said blade adapted to be placed in position by placing said notch in engagement with said pin with the back end of said blade projecting above said prongs, and pivoting the same about said pin as an axis by lowering the back end; and

means for yieldingly retaining said blade in position.

6. In a device of the character described, a handle comprising a hand-grip portion and a blade-supporting portion, the blade-supporting portion comprising two parallelly arranged stiff prongs with a slot between adapted to accommodate a thin flexible blade, a thin flexible blade adapted to be swung into position into said slot from the top and be embraced by said prongs and means for detachably retaining the blade in the slot.

7. In a device of the character described, a handle comprising a hand-grip portion and a blade-supporting portion, the blade-supporting portion comprising two parallelly arranged stiff prongs with a slot between adapted to accommodate a thin flexible blade, and a thin flexible blade adapted to be swung into position into said slot from the top and be embraced by said prongs at its upper edge.

8. In a device of the character described, a handle comprising a hand-grip portion and a blade-supporting portion, the blade-supporting portion comprising two parallelly arranged stiff prongs with a slot between adapted to accommodate a thin flexible blade, and a thin flexible blade adapted to be swung into position into said slot from the top and be embraced by said prongs along the major part of its upper edge.

9. In a device of the character described, a handle comprising a hand-grip portion and a blade-supporting portion, the blade-supporting portion comprising two parallelly arranged stiff prongs with a slot between adapted to accommodate a thin flexible blade, a pin joining the prongs near their ends, a thin flexible blade adapted to be swung into position from the top into the slot between the prongs and provided at its upper edge with a notch adapted to embrace said pin and means for detachably retaining the blade in the slot between the prongs.

10. In a device of the character described, a handle comprising a hand-grip portion and a blade-supporting portion, the blade-supporting portion comprising two parallelly arranged stiff prongs with a slot between adapted to accommodate a thin flexible blade, a pin joining the prongs near their ends, a thin flexible blade adapted to be swung into position from the top into the slot between the prongs, a notch in the upper edge of the blade adapted to embrace the pin joining the ends of the prongs, and means at the back end of the blade adapted to engage with co-acting means in the handle for yieldingly retaining the blade in position in the slot between the prongs.

HAROLD BRIX.
